FRAME FOR CHILDREN'S BICYCLE SEAT

Morris Bishaf, 8512 N. Harding, Skokie, Ill. 60075, and
Leonard Messineo, 2318 Greenfield Drive, Glenview,
Ill. 60025

Filed Sept. 15, 1971, Ser. No. 180,936

Term of patent 14 years

Int. Cl. D12—11

U.S. Cl. D12—119

FIG. 1

FIG. 2

FIG. 3

FIG. 4

FIG. 5

FIG. 1 is a perspective view of the frame for children's bicycle seat showing our new design;

FIG. 2 is a perspective view thereof, it being understood that the broken lines are for illustrative purposes only;

FIG. 3 is a side elevational view thereof;

FIG. 4 is a rear elevational view thereof with portions of the right leg being omitted for ease of illustration; and

FIG. 5 is a top plan view thereof.

We claim:

The ornamental design for a frame for children's bicycle seat, as shown and described.
